UNITED STATES PATENT OFFICE.

DAVID GUELBAUM, OF SYRACUSE, NEW YORK.

AUTOMATIC MIXING AND PROPORTIONING DEVICE OR VALVE.

1,419,455.

Specification of Letters Patent. Patented June 13, 1922.

Application filed December 21, 1920. Serial No. 432,186.

To all whom it may concern:

Be it known that I, DAVID GUELBAUM, a citizen of the United States, and a resident of Syracuse, in the county of Onondaga and 5 State of New York, have invented a certain new and useful Automatic Mixing and Proportioning Device or Valve, of which the following is a specification.

This invention has for its object a proportioning and mixing device particularly applicable for proportioning and combining elements or streams to be mixed in definite ratios, and of the type set forth in my pending application, Sr. No. 412,736, filed 10 Sept. 25, 1920, which device is particularly adapted for use in larger pipe lines or installations than that shown in my pending application, and which is particularly simple and efficient in construction and highly 15 efficient and durable in use. It consists in the novel features and in the combinations and constructions hereinafter set forth and claimed.

In describing this invention, reference is 20 had to the accompanying drawings in which like characters designate corresponding parts in all the views.

Figure 1 is a vertical sectional view of one form of my mixing and proportioning 25 device.

Figure 2 is a sectional view taken on line 2-2, Fig. 1.

Figure 3 is a sectional view on line 3-3, Fig. 1.

Figure 4 is a sectional view of another 30 form of my invention.

Figure 5 is a fragmentary sectional view similar to Fig. 3 taken on line 5-5, Fig. 4.

Figure 6 is a detail view of one of the 35 adjusting screws shown in Figs. 1 and 4.

Figure 7 is a fragmentary sectional view of a third form of my invention.

Figure 8 is an elevation showing a plurality of mixing devices connected in series.

Figure 9 is a fragmentary sectional view 40 illustrating a different form of adjusting means from that shown in Figs. 1 and 4.

Fig. 10 is a fragmentary section showing 45 a detail.

This proportioning and mixing device is 50 designed for automatically mixing and proportioning any two streams, dry or wet, such as air with gas, liquid or powdered fuel for heat, light and power generation, 55 or air with water, oil, etc., as in air lift

pumps, or streams of other substances combined for any purpose in just the required ratio, in the form of two concentric conical sheet streams of any desired thickness impinging upon and intermingling with each other in one stream so as to produce the highest efficiency under all working conditions at full or fractional capacity.

The device consists generally of four concentric cylinders the inner and outer cylinders being stationary and secured together in fixed relation and the other two inner cylinders being for adjusting the thicknesses of the streams being mixed. These inner cylinders are preferably adjustable and 60 slide axially but in some instances may be stationary. They may also be separated for variable service when the ratio between the combined streams is to be varied, or they may be cast together in one piece for permanent service.

Each of the two inner regulating or adjusting sleeves or cylinders has a cone end surface opposed to a cone surface of the outer or the inner cylinder, that is, one of 65 these regulating cylinders has a cone surface opposed to a contracting cone surface of the outer member and the other regulating cylinders has a cone surface opposed to a cone surface on the innermost stationary 70 cylinder. The smaller one of the two streams to be combined enters the inner stationary cylinder and it passes between two of such conical surfaces while the larger stream enters the outer stationary cylinder 75 and passes between the other two of such conical surfaces. Thus, the thicknesses of 80 these two streams can be regulated where required by sliding the two inner regulating cylinders and hence varying the quantities of, and the ratio between the volumes 85 of the combined streams.

By means of the proportioning valve with the two inner regulating cylinders cast in one, that ratio between the passage areas 90 for the two streams that would produce the highest efficiency can be automatically maintained under all working conditions whether the passages are fully open or partly closed. The proportioning valve here shown is especially adapted to flanged pipe connections as for furnace firing and large manufacturing processes.

This proportioning and mixing device or valve for combining streams of materials 95

or fluids to be mixed in fixed ratios comprises generally, inner and outer hollow stationary members or cylinders arranged concentric with each other and formed with 5 passages for the materials or streams to be intermingled within the outer member, the inner member being arranged with its passage substantially coaxially with the passage of the outer member and having openings 10 into the passage of the outer member, said members having flanges for connection to like flanges of pipes on a pipe line or to the flanges of adjacent devices, means as inner cylinders or sleeves adjustable lengthwise 15 of the inner and outer members to open and close the passage of the outer member more or less and proportionately close the outlet passage of the inner member, and means for effecting the adjusting movement 20 of the sleeve.

1 and 2 are respectively, the outer and inner members or cylinders, the outer member 1 being formed with a contracting or conical portion 3 confining a contracting 25 passage, the member 1 being also formed with inlets 4 in the larger cylinder portion thereof above the conical portion 3.

Also, if desired, suitable ribs or flanges 30 may be located between the inlets 4 of the outer member 1, Figs. 1 and 2 for reinforcement. The outer member 1 is open at its upper or rear end, with respect to the direction of the flow of the materials to be mixed, and is formed with annular flanges 7 and 8 on each 35 end thereof for connection respectively to the inner member as will be hereinafter described and to a pipe line or to the inner member of another mixing device when the devices are arranged in series as shown in 40 Fig. 8.

The inner member or cylinder 2 is in the form of a tube closed at its inner end and having a series of lengthwise opening slots 10 near its inner end. The inner member or 45 cylinder 2 has a head 11 between its ends formed with an annular flange 12 opposed to the flange 7 for securing thereto in any suitable manner as by bolts or cap screws. The inner member or cylinder 2 is also 50 formed at its outer end with a flange 13 for connection to a similar flange on the outer member of an adjacent mixing device when the devices are arranged in series as shown in Fig. 8 or to a pipe line. The inner member is closed at its inner end by a suitable means 14 here shown as of two conical shaped parts, one, 15 being fixed in the slotted end of the member 2 and preferably cast in one therewith, and the other projecting axially 55 into the passage of the outer member 1 and being secured to the member 15 in any suitable manner as by a tie bolt 17. 18 is one 60 adjusting sleeve member or cylindrical member which encloses the member 21 and is slidable axially of the members 1, 2. 19 is the

other adjusting sleeve or cylindrical member, these members in Fig. 1 being shown as formed integral with each other. The sleeve member or cylinder 18 is shown as having an internal conical bore 18^a at its inner end 70 overlying the slotted end of the member 2 and the member 19 as having a conical surface 20 opposed to the conical wall of the contracting portion 3.

The conical bore 18^a is arranged in parallelism to a conical surface 21 on the rear side of the member 14 of the inner stationary cylinder 2, this surface being arranged beyond the ends of the slots 10. During movement of the sleeve members 18, 19 inwardly, the surface 18^a moves toward the conical wall 21 of the inner stationary cylinder 2, and the conical wall 20 moves in parallelism toward the conical surface of the contracting portion 3 of the outer 85 cylinder 1 and proportionately closes or opens the outlet passage 22 formed between the surfaces 18^a and 21 and leading from the slots 10 of the member 2 and the passages 20^a between the conical face 20, of 90 the sleeve 19 and the wall 3 of the outer cylinder 1. This adjusting member 18 slides on the periphery of collars 23 cast in the member 2, with a packing between.

The means for adjusting the sleeves or 95 cylinders 18, 19 axially comprises one or more screws 24 having their shanks supported in the head 11 of the inner member 2 and held from endwise movement relatively thereto, the screws threading in passages in the member 18. Thus, during turning of the heads 25 of the screws the sleeve members 18 and 19 will be moved inwardly or outwardly, as the case may be.

In order to accurately and finely adjust 105 the members 18, 19 a suitable graduated gage plate 26, Fig. 3 is provided on the head 11 around each adjusting screw and also one or more graduated rods 27 project from lugs 28 on the rear end of the members 18, 110 19 through the head 11 of the inner member. One complete turn of the screw 25 moves the adjusting sleeves 18, 19 and the rods 27 axially an amount equal to one graduation of the rods.

As seen in Fig. 9, a single adjusting means 115 may be provided common to all of the screws, this means here shown as consisting of an annular gear 29 meshing with a pinion 30 mounted on the shank of each screw 24. 120 The internal annular gear 29 is suitably mounted and supported on the head 11. Thus, during turning of any one screw or of the annular gear 29, the motion thereof will be transmitted to the other screws. The gear 29 is preferably formed with handles as 31.

In Fig. 4, a construction is shown in which the two adjusting sleeve members or cylinders 32 and 33 are provided independ- 130

ent of each other, one within the other, the sleeve member 32 having a conical surface 34 opposed to the wall of the contracting portion 35 of the outer member 36, the outer 5 sleeve sliding on the periphery of a collar 37 provided on the inner sleeve 33 which has a conical surface 38 opposed to the conical surface 39 on a closure 40 for the inner member. Both sleeves 32, 33 are operated by 10 screws 42, 43 respectively similar to the screws 24 shown in Fig. 1. These screws 42, 43 may be provided with suitable gages or micrometers 44 as seen in Fig. 5. By means of the constructions of sleeve members or 15 cylinders shown in Fig. 4, the effective areas of the passages of the outer and inner members can be independently adjusted, and the ratio between the two streams varied as desired.

20 In Fig. 7 is shown a construction in which the sleeve 45 is fixed and held by suitable screws or bolts 46 to the head 47 of the inner member 48.

In Fig. 8 is shown a series or battery of 25 my mixing devices connected by flanged pipe connections in one of which the sleeve member may be fixed as shown in Fig. 7, and in the other of which the sleeve has adjusting movement as shown in Fig. 1. In the arrangement shown in Fig. 8, the first of the 30 devices in the series, or the device nearest to the fuel tank is provided with an inner adjustable member as in Fig. 1, and the other is preferably of the form shown in Fig. 7.

35 Owing to the concentric arrangement and to the flanged ends of the inner and outer members the device can be readily connected in large pipe lines and the position of the sleeve member readily adjustable to suit the 40 conditions.

To aid in determining the proper adjustment of the sleeve member or members, an outlet 49 is provided for the mixing chamber 50 of the outer member through which 45 outlet the mixture can be taken and subjected to tests. In the case the mixture is fuel, it can be lighted at the outlet to determine whether it burns properly for heating or lighting purposes or subjected to temperature efficiency tests. This outlet is here 50 shown as formed in the flange 8 and is normally closed by a cap 51.

What I claim is:

1. A mixing device comprising inner and 55 outer hollow concentric members, the outer member being formed with a contracting conical passage, the inner member being formed with lengthwise slots near its inner end, means closing the inner end of the inner member, an adjusting sleeve concentric with said members and shiftable lengthwise toward and from the contracting wall of the outer member, the inner end of the sleeve having a conical bore encircling the slotted 60 portion of the inner member and said inner

member having a conical surface opposed to the bore of the sleeve member, and means for moving the sleeve member axially, substantially as and for the purpose described.

2. A mixing device comprising inner and 70 outer hollow concentric members, the outer member being formed with a contracting conical passage, the inner member being formed with lengthwise slots near its inner end, means closing the inner end of the 75 inner member, an adjusting sleeve concentric with said members and shiftable lengthwise toward and from the contracting wall of the outer member, the inner end of the sleeve having a conical bore encircling the slotted 80 portion of the inner member and said inner member having a conical surface opposed to the bore of the sleeve member, and means for moving the sleeve axially comprising a rotatable screw held from endwise movement and threading into the sleeve member, substantially as and for the purpose specified.

3. A mixing device comprising inner and 85 outer hollow concentric members, spaced apart to form a passage in the outer member, the outer member being formed with a conical contracting wall arranged to form a contracting passage near the inner end of the inner member, the inner member having an outlet 90 near its inner end, means arranged within the outer member and movable lengthwise thereof toward and from the contracting wall to proportionately open and close the 95 passages of the outer and inner members more or less, and a screw held from endwise movement and threading into said means in a direction parallel to the axis of the inner and outer members, substantially as and for the purpose described. 100

4. A mixing device comprising inner and 105 outer concentric members, spaced apart to form a passage in the outer member, the outer member being formed with a conical contracting wall, means arranged within 110 the outer member and movable lengthwise thereof toward and from the contracting wall to open and close the passage of the outer member more or less and a screw held from endwise movement and threading into 115 said means in a direction parallel to the movement of said means, substantially as and for the purpose specified.

5. A mixing device comprising inner and 120 outer concentric members, the outer member being formed with annular flanges at its ends and the inner member having a peripheral outlet at its inner end and being formed with a head between its ends abutting against one end of the outer member, the 125 head having an annular flange opposed to one of the former flanges for securement thereto, the inner member being also formed with an annular flange at its outer end, substantially as and for the purpose set forth. 130

6. A mixing device comprising inner and outer concentric members, the outer member being formed with annular flanges at its ends and the inner member having a peripheral outlet at its inner end and being formed with a head between its ends abutting against one end of the outer member, the head having an annular flange opposed to one of the former flanges for securement thereto, the inner member being also formed with an annular flange at its outer end, an adjusting sleeve movable axially of said members toward and from the contracting wall of the outer member and crosswise of the inner member, and means carried by the head of the inner member for adjusting the sleeve, substantially as and for the purpose described.
7. A mixing device comprising inner and outer concentric members, the outer member being formed with annular flanges at its ends and the inner member having a peripheral outlet at its inner end and being formed with a head between its ends abutting against one end of the outer member, the head having an annular flange opposed to one of the former flanges for securement thereto, the inner member being also formed with an annular flange at its outer end, an adjusting sleeve movable axially of said members toward and from the contracting wall of the outer member and crosswise of the inner member, and means carried by the head of the inner member for adjusting the sleeve, said means comprising a screw carried by the head of the inner member and held from endwise movement relatively

thereto and threading into the sleeve, substantially as and for the purpose specified.

8. A mixing device comprising inner and outer concentric members, the outer member being formed with an inlet and having a contracting portion intermediate its ends, the inner member having lengthwise slots near its inner end, a closure fixed to the inner end of the inner member and a cone shaped part projecting from the closure, and a tie bolt extending lengthwise of the cone shaped part connecting the closure and cone shaped part together, substantially as and for the purpose specified.

9. A mixing device comprising inner and outer concentric members spaced apart to form a passage in the outer member, the inner member having an outlet near its inner end, walls closing the outer end of the outer member around the inner member, means arranged within the outer member and movable lengthwise of said members to open and close the passages of the outer and inner members more or less, a screw extending through said wall held from endwise movement, the screw threading into said means in a direction parallel to the axis of the outer and inner members, and indicator rods projecting from said means and slidably through said wall, substantially as and for the purpose set forth.

In testimony whereof, I have hereunto signed my name at Syracuse, in the county of Onondaga, and State of New York, this 15th day of December, 1920.

DAVID GUELBAUM.
